UNITED STATES PATENT OFFICE.

JAMES L. BREESE, JR., OF CHICAGO, ILLINOIS, ASSIGNEE TO OIL DEVICES CORPORATION, OF CHICAGO, ILLINOIS, A CORPORATION OF ILLINOIS.

HEATING DEVICE.

Application filed December 17, 1923. Serial No. 681,671.

The invention relates to heaters and more particularly to the kind adapted to maintain the temperature of a room within certain desired limits.

to receive a screw stud 27 provided at the upper end with a gear 28 seated in a circular recess 29 of the casting. 55

5 One object of the invention is to provide a selfcontained heater unit in which the radiator is in immediate association with the burner. Another object is the provision of a heater in which the flue passages are employed as a radiator. Another object is the provision of means for returning to the fuel supply unvaporized liquid fuel. Other objects will appear from time to time in the course of the specification and claims.

10

15 The invention is illustrated more or less diagrammatically in the accompanying

A nozzle 30 is mounted centrally upon said gear 28 and the stem of the nozzle extends thru a central bore 31 provided in the gear stud. The lower part of the bore 26 receives in threaded engagement a pipe 32 which leads to a reservoir, as will be hereinafter further referred to. 60

15 The invention is illustrated more or less diagrammatically in the accompanying drawings wherein:

Attention is called to the fact that the 65
33 placed at equal distances from one an-
other and extending to the lower side of
another and extending to the lower side of
the gear 28. A pinion 34 which is journaled
in the recess 29 meshes with the teeth of
the gear 28 so that upon rotation of the
pinion and consequent rotation of the gear
28 the stud 27 may be raised to vary the po-
sition of the fuel jet for purposes of ad-
justment. 70 75

Figure 1 is an elevational view of the heating device constructed in accordance with my invention;

The end wall 35 of the casting 13 has a vertical bore 36 into which extends a pipe 37 provided with a valve 38. The pipe 37 leads to a reservoir for compressed air (not shown) and the amount of air admitted to the bore 36 can be regulated by the valve 38. The wall 35 carries a horizontal nozzle 39 of known construction having a longitudinal bore 40 opening at the inner end into a port 41 thru which the compressed air enters from the bore 36. The bore 36 is enlarged at the upper end as at 42 and is closed up by a screw stud 43. Upon admission of the compressed air by opening the valve 38, a jet of air is discharged in horizontal direction past the upper end of the nozzle 39 whereby the liquid fuel is sprayed towards the left end of the passage 14. This atomized fuel and the compressed air may be ignited and the flame produced thereby will extend into the interior of the column 20 of the radiator 11. From the fit-

Figure 2 is a top plan view of the radiator;
Figure 3 is a horizontal section on the line 3—3 of Figures 1 and 4; and
25 Figure 4 is a section on the line 4—4 of Figure 3.

The end wall 35 of the casting 13 has a vertical bore 36 into which extends a pipe 37 provided with a valve 38. The pipe 37 leads to a reservoir for compressed air (not shown) and the amount of air admitted to the bore 36 can be regulated by the valve 38. The wall 35 carries a horizontal nozzle 39 of known construction having a longitudinal bore 40 opening at the inner end into a port 41 thru which the compressed air enters from the bore 36. The bore 36 is enlarged at the upper end as at 42 and is closed up by a screw stud 43. Upon admission of the compressed air by opening the valve 38, a jet of air is discharged in horizontal direction past the upper end of the nozzle 39 whereby the liquid fuel is sprayed towards the left end of the passage 14. This atomized fuel and the compressed air may be ignited and the flame produced thereby will extend into the interior of the column 20 of the radiator 11. From the fitting of the valve 38 a branch pipe 44 leads to an inspirating device generally designated 90

Figure 3. The heating device comprises a burner generally designated by 10, a radiator 11 with which the burner communicates and a reservoir 12 supplying fuel to the burner. The burner includes a hollow casting 13 providing a horizontal passage 14 which communicates at the right end, as viewed in Figure 4, with a vertical passage 15 defined by a tubular portion 16 integral with the casting 13. The latter, at its left end, terminates in a circular head 17 equipped with an annular chamber 18 of circular cross section, and an upright flange 19 of the head is provided with interior threads and surrounds the lower threaded end of a vertical column 20 of the radiator 11. The radiator includes another vertical column 21 and both columns are inter-connected by a plurality of horizontal pipes 22.

by 45 and which includes the casting 46 equipped with a Venturi tube 47 leading to the annular chamber 18 and having communication therewith by an opening 48. The casting 46 has a plurality of lateral openings 49; a nozzle 50 is carried by the casting 46 and is connected at its outer end with the pipe 44 while the inner end discharges into the tube 47.

5 The annular chamber 18 at a point diametrically opposite to the aperture 48 opens into a tube 51 thru an aperture 52 and the tube 51 is connected with a tubular extension 53 of the casting 13 and permits air to be discharged in the vicinity of the jet 30.

10 The column 20 at the upper end is provided with a circumferential flange 54 and a flanged pipe section 55 is secured to the column 20 by a series of bolts 56. Between the flanges of the column and of the pipe section 55 a sheet of mica is interposed, affording thereby an opportunity to observe combustion at the lower end of the column 15 20. The column 21 of the radiator is closed up at the bottom by a cover 58 and at the top a union 59 secures an exhaust pipe 60 to the upper end of the column to permit the escape of exhaust gases, as will herein-after further appear.

25 As previously referred to, the burner is supplied with fuel thru a pipe 32 and the latter leads to a constant level well 61 which supports an inverted tank 62 so that fuel is maintained at the level 63.

The operation of the heating plant is as follows:

30 When the valve 39 is opened, compressed air is discharged from the nozzle 40 and the stream of air passing by the nozzle 30 will carry along fuel from the nozzle 30 and atomize it, and this mixture of compressed air and atomized fuel is manually ignited through the passage upon removal of cap 35 24 and the flame will extend thru the passage 14 into the lower part of the column 20. At the same time, compressed air will be discharged through the nozzle 50 and this compressed air will carry along induced or 40 inspirited air thru the lateral openings 49 of the inspiriting device 45 as indicated by arrows in Figure 3. The air from the inspiriting device will flow thru the tube 47 into the annular chamber 18. There a portion of the inspirited or induced air will escape thru the openings 23 into the lower part of column 20 to support combustion therein. Another portion of the air in the 45 50 annular chamber 18 will escape thru the aperture 52 and flow thru the pipe 51 towards the nozzle 30 to support combustion at the burner.

55 Attention is called to the fact that in case the liquid fuel carried along by the stream of compressed air escaping from the bore 40 will reach the curved bottom wall 64, in case by accident the flame is extinguished so that no combustion takes place, then the fuel will flow back along the bottom of passage 14 and will drip into the recess 29; and then thru the grooves 33 back into the pipe 32 to again be drawn up by the stream of compressed air emanating from the nozzle 39.

60 65 In order to prevent carbon from being

carried along by the fuel drained back into the reservoir, a screen 70 is provided in the pipe 32 through which the back flowing fuel is filleted.

Attention is called to the fact that the 70 burner is completely encased so that outside air is not relied upon to enter into contact with the burner for the purpose of obtaining combustion. Furthermore, the encasing of the burner eliminates any danger 75 in using the heating device in dwelling places. Inspired air is relied upon to aid the combustion in the radiator column and is obtained from a point removed from the burner so that the heating device is safe 80 and reliable.

It is also noteworthy that the provision of the Venturi tube 47 entails a great velocity 85 of the inspired air at the narrow portion of the tube, so that if the flame should flash back into the tube it could not cause back firing owing to the greater velocity of the inspired air. The compressed air may be obtained from any suitable source of supply or, if preferred, a small compressor may be 90 provided to secure the necessary amount of compressed air.

95 The invention is applicable to the heating of places where it is not desired to maintain centralized heating. It is noteworthy that 100 the reservoir, the burner and the radiator constituting the heating device are all arranged compactly in the room to be heated, so that piping and other accessories necessary in the installation of heating plants are 105 dispensed with. A ready application of the invention is its use in automobile service stations where, of course, compressed air is always available.

110 In the drawing, a preferred embodiment of the invention is illustrated merely by way of explanation and not by way of limitation and it will be realized that many changes may be made in the size, shape, number and disposition of parts without departing from 115 the spirit of my invention. I therefore do not wish to be limited to the particular construction of burner or radiator and wish my description and drawings to be taken as in a broad sense illustrative and diagrammatic. 120

I, therefore, do not limit myself to the particular features shown, but include all changes, variations and alterations constituting departures within the scope of the invention as defined in the appended claims.

125 I claim :

1. In a heating device, a fuel mixing chamber, a baffle wall forming part thereof, a liquid fuel nozzle projecting into said mixing chamber and a fuel supply pipe associated therewith, atomizing means adapted to spray the fuel delivered by said nozzle into said mixing chamber, the normal level of said fuel being substantially below the tip of the fuel nozzle, and means for returning the unvapor- 130

ized liquid fuel directly to said supply pipe, comprising longitudinal draining grooves along the exterior of said fuel nozzle.

2. In a heating device, a fuel mixing chamber, a baffle wall forming part thereof, a liquid fuel nozzle projecting into said mixing chamber and a fuel supply pipe associated therewith, a compressed air nozzle adapted to direct a jet of compressed air across the

tip of said fuel nozzle, said fuel nozzle having longitudinal drainage grooves adapted to permit the drainage direct to said fuel pipe of liquid fuel accumulating in said mixing chamber, and means for axially adjusting the fuel nozzle. 10 15

In witness whereof I affix my signature.

JAMES L. BREESE, JR.
